UNITED STATES PATENT OFFICE.

HENRY M. KREH, OF HADDON HEIGHTS, NEW JERSEY.

HUMIDOR.

Application filed February 27, 1920. Serial No. 361,875.

To all whom it may concern:

Be it known that I, HENRY M. KREH, a citizen of the United States, and a resident of Haddon Heights, Camden County, New Jersey, have invented certain new and useful Improvements in Humidors, of which the following is a specification.

My invention relates to humidors or moisteners for tobacco products, and one object 10 of my invention is to provide an ordinary box or container, for instance a cigar box of a type which may be sold as an original package or employed by a dealer as a container from which to vend the tobacco products, with means for keeping the contents sufficiently moist or damp and in proper condition. A further object of my invention is to provide an improved structure which may serve as a container and humidor 15 for the purchaser and in which cigars or other tobacco products may be kept until consumed. While my invention is applicable for use with tobacco products generally, it is more particularly adapted for use 20 with boxes or packages employed for the purpose of packing and vending cigars, or as containers therefor.

While in most instances the container will be made of metal, it is obvious that other 25 materials may be employed, including cardboard and similar materials, which may be suitably treated for rendering the same air- and moisture-proof, if desired.

These and other features of my invention 30 are more fully described hereinafter, reference being made to the accompanying drawings, in which:

Figure 1, is a vertical section through a 35 humidor container embodying the features of my invention.

Fig. 2, is a perspective view of the moistening pad and closure member carrying the same which I may employ.

Fig. 3, is an enlarged sectional view of a 40 part of the humidor, illustrating a modified construction within the scope of my invention.

Fig. 4 is a perspective view illustrating a 45 structure of another shape to which my invention may be applied.

Figs. 5, 6, 7 and 8 are fragmentary sec-

tional views illustrating details of the structure forming the subject of my invention, and Fig. 9 is a view similar to Fig. 3, illustrating a further modification within the 55 scope of my invention.

In Fig. 1, of the drawings, 1 represents a suitable container for cigars, which may be circular or rectangular in cross section. This container, usually of metal, may be made of 60 any suitable material, for instance, pasteboard suitably water-proofed or otherwise treated to be substantially moisture-proof, and in most instances it will be provided with a suitable lining 2, which may be of 65 cedar veneer, for instance.

In constructing the humidor container forming the subject of my invention, I prefer to take a type of can or canister in well known commercial use, which is provided 70 with a flanged head having a neck or throat 3 adapted to receive a substantially cup-shaped insertible closure cap 4. In the ordinary construction of cans or canisters of this type, whether circular or rectangular 75 in cross section, such closure cap is applied to the top or upper end of the same, and the opposite end of the can or canister is provided with a suitable plain bottom, usually retained in place by beading over the end of 80 the body or shell. In my construction, however, the element normally forming the bottom of the can is omitted, and the edge of the open end of the body may be simply turned over as at 5 to give the same a smooth 85 finish and to act as a stiffener or reinforcement, and this end is adapted to receive an ordinary slip cover 6, externally applied. In my construction, the cup-shaped closure 4 is applied to the bottom of the can or 90 canister and the slip cover 6 is applied to the top of the same.

This construction of box or can provides an internally disposed flange 7 which, in my arrangement, will be disposed at the bottom, and this flange is adapted to support a suitable diaphragm or shelf 8 constituting a false bottom, the same substantially fitting the interior of the container and having a downturned flange or edge 9 100 which may rest upon the flange 7 of the container. This diaphragm may be made of

any suitable form of foraminous or reticulated material. In Fig. 1, I have shown a perforated sheet of metal, and in Figs. 3 and 9, I have shown a section of wire gauze. 5 It constitutes a false bottom to support the cigars or other tobacco product within the container.

The cup shaped closure cap 4 carries a moistening pad 10 which may be of any 10 suitable absorbent material, and in practice, I have employed a series of sheets of blotting paper, with an interposed section of material 11; a layer of cedar veneer for instance. The several parts may be secured together 15 by a pronged fastener of the ordinary McGill type indicated at 12. By the use of such form of fastener, the pad can be removed from the closure as desired; either when the cigars are too moist or when it is desired 20 to renew the same. It will be understood that other forms of fastening means may be employed. If desired, ventilating apertures may be made through the closure wall, veneer layer and absorbent pad.

25 As clearly illustrated in the drawings; the absorbent pad is placed a short distance from the false bottom 8. If desired, the continuous flange of the latter may be omitted and a series of prongs bent down from 30 the sheet to rest upon the internal flange 7 of the box or can. As usually constructed, the false bottom is removable but, if desired, I may secure it to the wall of the box by eyelets 13, as shown in Fig. 3, which serve 35 the further purpose of providing ventilating apertures. In lieu of apertures so formed, I may form apertures in the can and the lining thereof opposite the space between the moistening pad and the false 40 bottom.

The wall of the box or container may also be apertured at other points to provide additional ventilation, and in making these 45 apertures I may strike up the wall of the can, if of metal, and turn in the struck up portion so as to retain the lining in place, in the manner indicated in Fig. 5.

The cover is preferably provided with a 50 lining 14, of suitable material, cedar veneer, for instance, and this may be retained in place by beading the wall of the cover as at 55, as shown in Fig. 1, or portions of the cover flange may be pressed in to form prongs that will engage the lining, as shown in Figs. 6, 7 and 8; the openings formed in making such prongs affording ventilating means. In lieu of this arrangement, plain 60 apertures 16 may be formed in the top wall of the cover and in the body of the lining carried thereby.

I have shown in Figs. 1 and 3, a form 65 of closure cap 4, which is cupped from the outside. In lieu of this I may employ a closure cap 4^a such as shown in Fig. 9, in which the wall is reverted; thereby providing space

for the moistening pad and materially reducing the space between the closure and the false bottom.

As may be readily seen, the bottom closure 4 is readily detachable from the humidor container in order to moisten the absorbent pad and readily returned in place, being retained by frictional contact with the wall of the opening. 70

My invention is applicable to round boxes 75 or rectangular boxes as the case may be, and in Fig. 4, I have shown a perspective view of the bottom of a rectangular container receiving a circular closure cap adapted to carry a moistening pad of absorbent material, of the same type as employed with the structure illustrated in Figs. 1 and 2. In such form of container, the false bottom 80 will be rectangular.

As may be seen, my invention is applicable 85 to ordinary commercial cans found on the market, requiring no special tools for producing the same, hence the construction is of the utmost simplicity and of minimum cost. 90

I claim—

1. A humidor comprising a cylindrical casing with an opening at each end, a permanently attached wall at one end of said casing in which one of said openings is formed; said wall having an internally disposed flange surrounding the opening formed therein, detachable closures for each end of said casing; one of said closures being externally applied while the other closure is internally applied and is in tight frictional engagement with the flange surrounding the opening in said end wall of the casing, and a moistening pad secured to said internally applied closure and removable therewith. 95

2. A humidor comprising a cylindrical casing with an opening at each end, a permanently attached wall at one end of said casing in which one of said openings is formed; said wall having an internally disposed flange surrounding the opening formed therein, detachable closures for each end of said casing; one of said closures being externally applied while the other closure is internally applied and is in tight frictional engagement with the flange surrounding the opening in the end wall of the casing, a moistening pad secured to said internally applied closure and removable therewith, and a false bottom of foraminous material 115 detachably mounted in said casing and resting on said end wall for supporting contained articles out of contact with said moistening pad. 120

3. A humidor structure comprising, in 125 combination, a cylindrical casing with an opening at each end, a permanently attached wall at one end of said casing in which one of said openings is formed; said wall having a flange surrounding the opening formed 130

therein, detachable closures for each end with; said pad having its surface exposed of said casing, one of said closures being externally applied while the other closure is internally applied and engages the flange and facing upwardly within the casing when the carrier therefor is secured in closed position with respect to the casing. 10

5 surrounding the opening in said end wall, In witness whereof I have signed this and a moistening pad secured to said internally applied closure and removable there- specification.

HENRY M. KREH.
